SLIDE GATE

Karl J. Hnatko, Hibbing, Minn., assignor to Taconite
Engineering & Manufacturing Co., Hibbing, Minn.

Filed Oct. 13, 1972, Ser. No. 300,402
Term of patent 14 years

Int. Cl. D23—01

U.S. Cl. D23—38

FIG. 1

FIG. 2

FIG. 3

FIG. 4

FIG. 5

FIG. 7

FIG. 8

FIG. 9

FIG. 10

FIG. 11

FIG. 12

FIG. 1 is an isometric view of a slide gate in an intermediate partly opened position and showing one form of my new design;

FIG. 2 is a top plan view thereof;

FIG. 3 is a right side elevation thereof;

FIG. 4 is a left side elevation thereof;

FIG. 5 is a front elevation thereof;

FIG. 6 is a rear elevation thereof;

FIG. 7 is an isometric view of a slide gate in an intermediate partly opened position and showing another form of my new design;

FIG. 8 is a top plan view thereof;

FIG. 9 is a right side elevation thereof;

FIG. 10 is a left side elevation thereof;

FIG. 11 is a front elevation thereof; and FIG. 12 is a rear elevation thereof.

I claim:

The ornamental design for a slide gate, as shown and described.
